R. TATTU,
CORNER JOINT.
APPLICATION FILED FEB. 17, 1916.

1,238,054.

Patented Aug. 21, 1917.

Inventor
Rader Tattu
By his Attorney
Andrew Gould Jr.

UNITED STATES PATENT OFFICE.

RADU TATTU, OF BROOKLYN, NEW YORK, ASSIGNOR TO UNIVERSAL METAL BED COMPANY, OF BROOKLYN, NEW YORK, A CORPORATION OF NEW YORK.

CORNER-JOINT.

1,238,054.

Specification of Letters Patent. Patented Aug. 21, 1917.

Application filed February 17, 1916. Serial No. 78,868.

To all whom it may concern:

Be it known that I, RADU TATTU, a citizen of the United States, and resident of borough of Brooklyn, in the county of Kings and State of New York, have invented certain new and useful Improvements in Corner-Joints, of which the following is a specification.

My invention relates to improvements in corner joints and the object of my invention is to provide a simple, convenient and efficient device for fastening the parts of a bedstead and the like at the corners.

I accomplish this object by the device illustrated in the accompanying drawings in which,

Figure 1 is a plan view of the device,

Fig. 2 is a perspective view of the same,

Fig. 3 is a view of the end section of the side bar,

Fig. 4 is a section on the line 4—4 in Fig. 2, and

Fig. 5 is a view of the anchor member.

Similar characters refer to similar parts throughout the several views.

My device is particularly adapted for use in metal bedsteads.

I provide an anchor member 1 having a body section 2, an end section 3 bent over at substantially a right angle to the body section 2, a leaf 4 bent upward parallel to the body section 2 forming a channel therebetween and an end leaf 5 bent over at a right angle to the leaf 4.

The end section 3 of the anchor member preferably conforms to the shape of the post 6 of the bedstead to which it is attached by

means of a screw or bolt 7 or in any other desired manner.

A lateral cross bar 8, which is preferably of angle iron construction and which binds together the head posts or the foot posts of a bedstead, is secured to the leaf 5 by means of rivets 9 or the like.

The longitudinal side bars 10 of the bedstead are each provided at its end section with a cut out socket 10¹ preferably having the side 11 adjacent the post 6 inclined and having a vertical rear wall 12.

The side bars 10 of the bedstead are seated in the channel formed by the bent up leaf 4 and body section 2 of the anchor member 1 and will be drawn up against the post 6 by the engagement of the inclined wall 11 of its socket and a pin 13 inserted across the said channel.

Having thus described my invention what I claim is:

A corner joint bracket including a member substantially U-shaped in cross section having one wall extended rearwardly beyond the other wall, an end section projected at right angles from the member and connected to the extended portion of the side wall, and an end leaf extended from the remaining side portion of the member at the opposite end thereof.

Signed at New York city in the county of New York and State of New York this 9th day of February A. D. 1916.

RADU TATTU.
